UNITED STATES PATENT OFFICE.

EUGÈNE PETIT, OF PARIS, FRANCE, ASSIGNOR TO ALEXANDER SMITH & SONS CARPET COMPANY, OF YONKERS, NEW YORK.

DESIGN FOR A CARPET.

SPECIFICATION forming part of Design No. 14,073, dated July 10, 1883.

Application filed June 5, 1883. Term of patent 3½ years.

To all whom it may concern:

Be it known that I, EUGÈNE PETIT, of Paris, in the Republic of France, have invented a new and original Design for Carpets, of which 5 the following is a specification.

The accompanying photograph illustrates my new design for carpets.

This invention relates to a new design for carpets, oil-cloths, and analogous fabrics; and 10 it consists of the new ornamentation of parts hereinafter more fully pointed out.

The representation of a short fence-like structure, A, in the lower part of the photograph, is shown to be covered by a cluster, B, of 15 flowers, from which a branch, *a*, extends upward, and another branch, *b*, downward, to the right. The part of the ornamentation B which is shown at the top of the photograph will, when the carpet is matched, become the lower portion of the cluster B, (shown in the lower part

of the photograph,) and from it will depend the branch *b* downwardly and to the side. Between the fence-like structure A and the branch B, which is next above it in the matched carpet, is the representation C of a flower, which 25 appears in faint outline, so as to bring the floral ornamentation B *a b* more fully into relief. In similar faint outline are the representations of leaves, *d*, at the sides of the figure C. A bouquet, D, of flowers is at one side of the photograph, connecting, when the carpet is matched, by the branch *e*, with the floral group B. 30

I claim—

The design for carpets, consisting of the figures A B C D *a b d e*, substantially as shown. 35

EUGÈNE PETIT.
